[57] CLAIM

The ornamental design for a slider for a reclosable thermoplastic bag, as shown and described.

DESCRIPTION

FIG. 1 is a front elevational view of a slider for a reclosable thermoplastic bag embodying our design, the rear elevational view being the same in appearance.

FIG. 2 is a left side elevational view thereof.

FIG. 3 is a right side elevational view thereof.

FIG. 4 is a top plan view thereof.

FIG. 5 is a bottom plan view thereof; and,

FIG. 6 is a perspective view thereof.
